UNITED STATES PATENT OFFICE.

JOHN G. GIBSON, OF VENTNOR, NEW JERSEY.

WATER GRATE.

Application filed July 5, 1923. Serial No. 649,487.

This invention, generally stated, relates to steam and hot water boilers employing forced or induced draft and has more particular relation to the providing of certain new and novel sectional hollow grates therefor which may be formed integral with the water-legs of a boiler section at the time of manufacture of the boiler or which may be installed in existing boilers without effecting 5 change in the construction thereof. Other and further objects relate to the provision of general details of construction and in the arrangement and combination of parts hereinafter set forth.

15 The invention consists of the improvements hereinafter described and finally claimed.

The nature, characteristic features and scope of the invention will be more fully 20 understood from the following description taken in connection with the accompanying drawings forming part hereof, and in which:

Fig. 1, is a top view partly sectioned of a 25 pair of detachable grate-bars.

Fig. 2, is a view in section taken upon the line 2—2 of Fig. 1.

Fig. 3, is a top view of a slightly modified form of grate-bar construction.

30 Fig. 4, is a view in section taken upon the line 4—4 of Fig. 3.

Figs. 5 and 6 are views in plan and cross-section, respectively, of a further modified form of grate construction, and

35 Fig. 7, is a fragmentary view illustrating the grate-bar as shown in Figs. 1 and 2 formed integral with the water leg of a boiler section.

40 For the purpose of illustrating my invention I have shown in the accompanying drawings several forms which are at present preferred by me, since the same have been found in practice to give satisfactory and reliable results, although it is to be understood 45 that the various instrumentalities of which my invention consists can be variously arranged and organized and that my invention is not limited to the precise arrangement and organization of the instrumentalities as herein shown and described.

50 In the water-grate claimed in my Patent Number 1,366,877, dated January 25, 1921, use is made of removable, tubular sections having perforated domes. In the present instance these sections are omitted and the grooves of adjacent grate-bars form tubular

channels for the passage of air to the grate surface. The grooves however do not extend through the top of a grate-bar as shown in my said patent and while the flanges at 60 the lower end of the grooves may remain it is preferable in some cases to omit same. With the exception of these changes the general arrangement of grate-bar is similar to that disclosed in patent aforesaid. 65

Referring now to the drawings, 10 designates a grate-bar which is hollow for the circulation of water therethrough as is well understood in the art. Each side wall of a grate-bar 10 is vertically grooved from the 70 bottom thereof to within a short distance of the top thereof. These grooves which may be of any desired shape are spaced apart and are designated 11. The top wall of a grate-bar overhangs the grooves 11 throughout the 75 extent of a grate-bar. In other words the overhang is continuous. In Figs. 1 and 2, this overhang is designated 12 and projects upwardly upon a curved line so that meeting ledges of grate-bars form dome-like tops for 80 the air channels as formed by grooves 11. These domes are apertured as at 13 for the passage of air, under pressure, in the form of jets. The openings are arranged at an 85 inclination so that the jets of air may spread over the grate area instead of being forced directly through a bed of coals which latter is not desirable since an equal distribution of air is not obtained and the tendency is to cause a bed of coals to burn much faster in 90 some places than in others. By properly spacing the grooves and providing the apertured domes as described no such ill effects are experienced but a well balanced 95 distribution of air jets obtained. In Figs. 3 and 4 instead of the top edge of a grate-bar being formed upon a curved line above each groove 11, the top surface of a grate-bar is plane. That part of a grate-bar or ledge which overhangs the grooves 11 is 100 designated 14 in said Figs. 3 and 4 and is apertured as at 15. These apertures may if desired be arranged at an inclination although this is not always practiced in this 105 style of grate-bar.

One grooved face of each of the above described grate-bars is provided with horizontally disposed, spaced recesses 16, there being a recessed portion between adjacent 110 grooves 11. The opposite grooved face of each of the above described grate-bars is provided with horizontally disposed, spaced

ribs 17 adapted to co-actively engage with said recessed portions 16 whereby adjacent or abutting grate-bars may be interlocked. These recessed and ribbed portions form overlapping parts to preclude air seeping up between adjacent grate-bars, or in other words all air must pass up through the apertures of the ledges, to be evenly distributed, as before described. In practice cement or the like may be applied between the adjacent faces of grate-bars. The side walls of a grate-bar of each type are shaped to follow the curves of the grooves 11 so that approximately the same thickness of metal is present throughout a grate-bar to provide for uniformity of cooling surface. The thickness of the over-hung portions is of approximately the same thickness as the walls of a grate-bar. Referring now to Figs. 5 and 6 each grate-bar is provided upon one side wall with grooves 11 similar to those above described and is provided upon its opposite side wall with grooves 18 which extend through the grate-bar top in the same manner as those shown in my aforesaid patent. These grooves are recessed or countersunk at their tops as at 19. At their bottoms each set of grooves are provided with flanged parts 20. The grate top upon that side provided with grooves 11 is provided with laterally disposed flanged parts 21 which not only overhang said grooves 11 but are further extended to seat within the recessed or countersunk parts 20 of grooves 18 of an adjacent grate-bar. These flanges 21 are semi-circular, as the recessed parts 19, and are apertured as at 22 for the passage of air to the grate surface. A particular advantage derived from this type of construction is that if a flanged part 21 fractures as at 23, see Fig. 6, one of the hollow members with perforated domes as disclosed in my aforesaid patent and designated in Fig. 6, as 24, may be introduced within the channel as formed by grooves 18—11 and seated upon flanged parts 20. This avoids substituting a new grate-bar. Any of the above described types of grate-bars may be cast integral with a water-leg of a boiler, as shown in Fig. 7. The type as illustrated in Figs. 1 and 2 is used for illustrative purposes.

It will now be apparent that I have devised a novel and useful construction which

embodies the features of advantage enumerated as desirable in the statement of the invention and the above description and while I have in the present instance shown and described the preferred embodiments thereof which have been found in practice to give satisfactory and reliable results, it is to be understood that the same are susceptible of modification in various particulars without departing from the spirit or scope of the invention or sacrificing any of its advantages.

What I claim is:

1. In a grate construction of the character stated a plurality of hollow grate-bars including side walls and a cover each side wall being vertically grooved so that the grooves of adjacent grate-bars form a plurality of spaced channels and a separate ledge extended from said cover upon each side thereof for overhanging each groove 75 the edges of opposed ledges abutting, said overhanging parts being perforated.

2. In a grate construction of the character stated a plurality of hollow grate-bars including side walls and a cover one side 80 wall of each grate-bar being horizontally recessed and the other side being provided with a ribbed portion for engaging an adjacent recessed portion, the side walls of each grate-bar being grooved vertically so 85 that adjacent grooves form channels and a separate ledge upon each side thereof for overhanging each groove, the said overhanging parts being perforated and the meeting edges of said ledges abutting. 90

3. In a grate construction of the character stated a plurality of hollow grate-bars including side walls and a cover each side wall being vertically grooved so that the grooves of adjacent grate-bars form a plurality of spaced channels, each side wall of a 95 grate-bar having projected laterally from adjacent its top, a separate ledge or flanged portion formed upwardly upon an arc of a circle for overhanging said channels, the 100 edges of opposed ledges abutting to form substantially dome-shaped parts upon said channels and that portion of each ledge overhanging a groove being perforated.

In testimony whereof, I have hereunto 105 signed my name.

JOHN G. GIBSON.
